[57] CLAIM

The ornamental design for a playing board for a board game, as shown and described.

DESCRIPTION

FIG. 1 is a top plan view of the first embodiment of the playing board for a board game, showing my new design; FIG. 2 is a top plan view of a second embodiment thereof; and,

FIG. 3 is a perspective view of FIG. 2, showing the top and two sides, the other sides being a mirror image thereof, the bottom being plain.
